UNITED STATES PATENT OFFICE.

THADDEUS F. BAILY AND FRANK T. COPE, OF ALLIANCE, OHIO, ASSIGNEES TO THE
ELECTRIC FURNACE COMPANY, OF ALLIANCE, OHIO, A CORPORATION OF OHIO.

FURNACE.

1,176,018.

Specification of Letters Patent. Patented Mar. 21, 1916.

Application filed December 11, 1914. Serial No. 373,639.

To all whom it may concern:

Be it known that we, THADDEUS F. BAILY and FRANK T. COPE, citizens of the United States, both residing at Alliance, in the county of Stark and State of Ohio, have invented a new and useful Furnace, of which the following is a specification.

Our invention relates to improvements in furnaces wherein a current of electricity passed through resistance material is employed to produce the necessary heat, and has more specific reference to means for utilizing the greatest possible amount of the heat generated therein.

15 The object of this invention is to generally improve such electric furnaces by more properly concentrating the heat therein upon the material which it is desired to heat.

20 Another object is to so dispose the walls of the furnace that the greater part of the heat generated through the resistance material will be either reflected or deflected by the walls upon the hearth which supports 25 the material desired to be heated.

With these objects in view the invention consists in the novel construction and arrangement of parts, hereinafter described, illustrated in the accompanying drawings, 30 and particularly pointed out in the appended claims, it being understood that various changes in the form, proportion, size and minor details of construction may be made within the scope of the appended 35 claims without departing from the spirit or sacrificing any of the advantages of the invention.

In the drawings: Figure 1 is a transverse sectional view through a furnace constructed in accordance with my invention. Fig. 2 is a section taken on the line 2—2, of Fig. 1.

Throughout the several views similar numerals of reference indicate corresponding 45 parts.

Referring more especially to the construction illustrated in the accompanying drawings, a base for the furnace is provided, consisting of a metal plate 1 supported at its 50 edges by means of angle irons 2 which are preferably strengthened by the angled irons

2. Reinforcing angles 4 may be provided to give rigidity to the plate 1 and a layer of asbestos 5, or its equivalent, is preferably placed upon the plate 1 for the purpose of 5 more thoroughly insulating the furnace from the base. This base is not claimed as a portion of the present invention and may be of any suitable form or structure to constitute a support for the furnace. 60

In the form of furnace shown in the accompanying drawings, the lower portion of the furnace is composed of hollow wall blocks 6, which support the bottom wall 7, said wall being composed of brick or other 65 suitable nonelectrical conducting and heat resisting material. A series of spaced supporting walls 8 are located upon the hollow blocks 6 and extend transversely across the furnace, the upper portion of each wall being 70 preferably composed of fire brick 9, said walls supporting the centrally located hearth 10 which is adapted to support the work to be heated. The supporting walls also carry the troughs in which are placed 75 the resistance material and electrodes, said troughs preferably consisting of the lower walls 11 which are preferably formed of fire brick and the upright sills 12 also formed of fire brick. Each of these troughs 80 is filled with a resistance body, consisting of a carbonaceous material in granular form such as crushed coke, charcoal or the like, said carbonaceous material being designated in the drawings by the numeral 13. Embedded 85 in the resistance material, preferably near each extremity of each trough is an electrode 14, said electrodes extending through the furnace walls as best shown in Fig. 1. It will be understood that the electrodes 14 should be arranged in an electric 90 circuit, such construction being well known in this art. Electric wires 15 are shown connected to each of the electrodes 14, said wires leading to a suitable source of electricity. When the current is supplied to the electrodes the current will be conducted from one electrode to the other through resistance material, thus raising the said 95 resistance material to an intense heat. Inclined walls 16, composed of brick, are disposed downwardly from a point adjacent

the bottom of the troughs which carry the resistance material, said walls terminating at the lower edges at the bottom wall 7.

The side walls of the furnace are preferably formed of hollow block 17 as shown in Fig. 1 of the drawings and fire brick 18 are preferably mounted between the upper tier of these hollow block and the bottom wall 11 of the trough which contains the resistance material. The end walls are preferably formed of greater thickness beneath the troughs as at 19 for the purpose of partly supporting said troughs and a facing 20 of fire brick is preferably formed upon the inner face of each end wall. Above the troughs which contain the resistance material each end wall 21 is preferably provided with an opening 22 by means of which the furnace may be charged or drawn and doors 23 are provided for said openings, said doors being adapted to be slid laterally or raised in any convenient and well known manner. The roof 24 of the furnace is shown in the drawings as forming an arch over the heating chamber. A sheet metal casing 25 is preferably provided around the furnace although this forms no part of the invention, the specific construction of the different parts of the furnace mentioned also forming no part in the present invention with exception of the arrangement of the roof and inside walls of the furnace with reference to the locations of the resistance material and the hearth, this invention having to do with the reflection and deflection of the heat rays.

The heat rays which radiate upward from each of the bodies of resistance material will strike the arched roof and although a portion of the heat will be absorbed the greater majority will be reflected toward the center of the heating chamber in the same manner as light rays falling upon a polished surface, that is to say the heat rays will be reflected from the arched roof upon the material on the hearth. It will be understood that the bottom walls 11 will become intensely heated and the heat rays which are radiated downwardly from the bottom walls will strike upon the inclined walls 16 and be deflected upwardly at an angle striking on the lower surface of the hearth 10 tending to further heat the hearth and the material which is placed upon it. By this construction the greater majority of the heat which radiates from the resistance material in the form of heat rays will be reflected or deflected back toward the hearth from all directions, thereby tending to concentrate the greater part of the heat within the heating chamber upon the hearth. It will also be understood that it is not necessary in order to produce the desired result to arrange the walls at the exact angles shown in the draw-

ings and it is not necessary to form the roof 65 in the shape of an arch as it has been found from experience that a roof formed of angular walls arranged with proper relation to the resistance material and the hearth will produce equally favorable results. It 70 is understood that the word "hearth" signifies any means for supporting the material to be heated.

It is advisable as shown more clearly in Fig. 1 of the drawing to locate the refractory troughs containing the resistance material in such a position that the trough is spaced on all sides from the walls of the heating chamber, thus forming a relieving space around the trough. By this arrangement of relieving spaces and reflecting walls 80 the flow of heat from the trough to the working hearth is greatly facilitated.

Although the drawings and above specification disclose the best mode in which we 85 have contemplated embodying our invention we desire to be not limited to the details of such disclosure, for, in the further practical application of our invention, many changes in form and construction may be 90 made, as circumstances require or experience suggests, without departing from the spirit of the invention, within the scope of the appended claims.

We claim:

1. In an electric furnace of the resistance type, the combination of a heating chamber, a resistance element located within said heating chamber, a roof so arranged above said resistance element that the heat rays 100 radiating upwardly from said resistance element will be reflected upon said hearth and walls beneath said resistance element so arranged that heat rays radiating downwardly from said resistance element will be reflected 105 upon said hearth.

2. In an electric furnace of the resistance type, the combination of a heating chamber, supporting walls located in said furnace, a hearth carried upon said supporting walls, 110 resistance elements carried upon said supporting walls and located upon each side of said hearth, an arched roof over said heating chamber, said roof adapted to reflect the upwardly disposed heat rays from said 115 resistance elements upon said hearth, and inclined walls located beneath said resistance elements and adapted to reflect the downwardly disposed heat rays upon said hearth.

3. In an electric furnace of the resistance 120 type, the combination of a heating chamber, supporting walls located in said heating chamber, a hearth carried upon said supporting walls, resistance elements carried upon said supporting walls and located upon 125 each side of said hearth, an arched roof over said heating chamber, said roof adapted to reflect all of the upwardly disposed heat

rays from both of said resistance elements have hereunto subscribed our names in the presence of two witnesses.
upon said hearth, and inclined walls located beneath said resistance elements but between said supporting walls and adapted to reflect the downwardly disposed heat rays upon said hearth.

In testimony that we claim the above, we

THADDEUS F. BAILY.
FRANK T. COPE.
